UNITED STATES PATENT OFFICE

STANLEY SAUVAGE, OF CHICAGO, ILLINOIS

HEAT DISTRIBUTOR OR PLATE

Application filed August 26, 1929. Serial No. 388,351.

This invention relates in general to devices generally known as heat distributors or plates, particularly adapted though not necessarily limited in use in cooking food which may be placed upon the top of the plate or in a suitable utensil, the device being particularly adapted for baking and roasting purposes, in which latter event a hood or cover is employed to cover the articles being cooked.

One of the objects of the invention is to improve and simplify the construction of such devices and reduce the cost of manufacture thereof and at the same time provide an improved plate of this character having means whereby the heat will be equally distributed, and a portion thereof directed through and towards the periphery of the plate and within the hood or cover, thereby causing a uniform baking or cooking of the articles under the cover or hood.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a vertical sectional view of a plate of this character constructed in accordance with the principles of this invention and showing a hood used in connection therewith.

Figure 2 is a top plan view of the plate with the hood removed, and showing a portion of the rack supported by the plate.

Figure 3 is an enlarged sectional view of a portion of the plate.

Referring more particularly to the drawing the numeral 10 designates generally an open cup shaped body portion of any desired size and configuration, preferably circular in cross section and is provided with an open-

ing 11 through the bottom thereof, the portion of the bottom adjacent the opening being flanged upwardly as at 12 to provide an opening through which the heat may pass into the body portion.

The body portion 10 may be provided with a bead or shouldered portion 13 extending circumferentially thereabout and the cup shaped body portion may be of any desired depth.

The numeral 14 designates a top plate which is adapted to fit over the open top of the body portion 10 to form a cover therefor and the edge of the top plate is adapted to rest upon the shoulder or beaded portion 13. These parts may be secured together in any suitable manner.

The top plate 14 is provided with a groove 15 extending therearound and spaced from the periphery thereof, the groove 15 opening upwardly through the upper face of the plate and is provided for the purpose of receiving the legs 16 of a supporting member 17 constructed in any suitable manner, the legs 16 being of any desired height so as to hold the supporting member 17 spaced for a desired distance above the top of the plate 14.

The top plate 14 is also provided with a series of apertures or openings 18 extending therethrough and disposed between the groove 15 and the periphery of the plate, and these openings 18 may be of any desired diameter but are preferably of a comparatively large diameter so as to permit the heated air currents to pass freely therethrough.

The top plate is also provided with another series of openings 19 which are arranged adjacent the inner wall of the groove 15 so that a portion of the groove 15 will be disposed between the two series of openings 18 and 19.

The openings 19 are preferably of a diameter smaller than the diameter of the openings 18 and pass through the inner wall 20

of the groove 15 and a portion of the base of the groove, for a purpose to be set forth.

Secured to the bottom of the plate 14 is a lower plate 20 which is preferably of a semi-circular configuration in cross section and is so arranged that the peripheral edge of the lower plate 20 will contact with the lower face of the upper plate 14, the plate 20 being of a diameter that the periphery thereof will be disposed within the confines of the groove 15 and terminate adjacent the openings 19 through the inner wall of the groove.

A metal plate or sheet 21 is arranged beneath the top plate 14 and is of a diameter to extend across the opening formed by the lower plate 20 so that the periphery of the plate 21 will rest upon the lower plate 20. A sheet of insulating material 22 such as asbestos or the like is arranged between the plate 21 and the lower face of the top plate 14 and is held in contact with both of said plates.

The lower plate 20, the plate 21 and the insulating material 22 are secured to the top plate 14 in any suitable manner preferably by means of a fastening device 23 which passes through all of these parts. The fastening device holds the periphery of the plate 20 against the lower face of the top plate 14 and also holds the plates 21 and 22 in a position that the insulating material 22 will contact with the lower face of the top plate, thereby necessitating only a single fastening device.

The plate 21 is formed preferably by the portion of the material cut from the bottom of the body portion 10 to form the opening 11.

With this improved construction it will be manifest that the heated air will enter the body portion 10 through the opening 11 and will be deflected by the lower plate or deflector 20 towards the periphery of the top plate 14. A portion of the heated air will pass through the openings 18 adjacent the hood 24 and will circulate in the hood and be directed downwardly upon the article being cooked. Another portion of the heated air will be deflected by the deflector plate 20 toward the periphery of the plate 14 and will flow through the openings 19 and will be directed toward the wall of the hood 24.

The hood 24 may be of any desired configuration, its lower end being shaped as at 25 to form a shoulder to engage over and rest upon the peripheral edge of the top plate 14.

With this improved construction it will be manifest that a device of simple construction will be provided and a circulation of the heated air will be caused by the deflector plate 20 and the heated air will be directed thereby toward the periphery of the plate and towards the wall of the hood so that when it rises it will flow into the hood adjacent the wall thereof and will be directed down-

wardly upon the top of the article being cooked. The insulating material 22 and the deflector 20 together with the arrangement of the deflector 20 insuring a complete or perfect circulation and distribution of the heated air within the hood 24.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A heat distributor plate embodying a body portion having a depending peripheral flange and provided with apertures therethrough adjacent its periphery and inside of the flange, said body portion having a groove extending therearound adjacent and encompassed by the said openings, and a deflector depending from the lower face of said body portion, the periphery of the deflector being disposed adjacent the inner wall of said groove, there being openings through the said inner wall of the groove and the adjacent portion only of the bottom of the groove.

2. A heat distributor plate embodying a body portion having a depending peripheral flange and provided with apertures therethrough adjacent its periphery and inside of the flange, said body portion having a groove extending therearound adjacent and encompassed by the said openings, a lower substantially semi-spherically shaped plate engaging at its upper edge with the lower face of said body portion, there being a second series of apertures through said body in close proximity and encompassing the edge of said lower plate, a sheet of insulating material extending across said lower plate and held in contact with the lower face of the said body portion by said edge of and terminating within the periphery of the lower plate, and a fastening device passing through said lower plate, insulating material and said body portion, the periphery of said lower plate being disposed adjacent the inner wall of said groove.

3. A heat distributor embodying a cup shaped body portion provided with an opening through its bottom of a diameter considerably less than the internal diameter of said portion, a top plate forming a closure for the top of said body portion, there being openings through the top plate adjacent the periphery thereof and extending circumferentially therearound, a lower concaved plate engaging at its upper edge with the lower face of said top plate and within the said body portion, and a sheet of insulating material extending across said lower plate and maintained in engagement with the lower face of said top plate by the engagement of the pe-

riphery of the insulating material with said lower plate, there being a groove opening through the upper face of said top plate adjacent and encompassing the periphery of said lower plate, there being openings through the inner wall and a portion only of the bottom of said groove.

In testimony whereof I have signed my name to this specification, on this 9th day of August, A. D. 1929.

STANLEY SAUVAGE.
